UNITED STATES PATENT OFFICE.

ROBERT M. HENDERSON, OF WEST ALLIS, WISCONSIN, ASSIGNOR TO THE FULTON COMPANY, OF WEST ALLIS, WISCONSIN, A CORPORATION OF WISCONSIN.

ACCELERATOR.

Application filed March 7, 1924. Serial No. 697,436.

This invention relates in general to improved apparatus which is especially applicable in the automotive industry, and relates more specifically to improvements in the construction and operation of accelerating appliances for effecting remote control of the speed of vehicle propelling motors or the like.

A general object of the invention is to provide improved speed control mechanism for 10 vehicle propelling motors or the like, which is simple in construction and efficient in operation.

Some of the more specific objects and advantages of the present improvement are as 15 follows:—

First. To provide a foot operable accelerator which is readily applicable as an accessory to any commercial automobiles of the Ford type.

Second. To provide accelerator mechanism which may be manufactured at reasonable 20 cost and sold at moderate price.

Third. To provide an efficient manually operable accelerator appliance which is extremely compact and durable in structure and 25 neat in appearance.

Fourth. To provide a remote control accelerating device various elements of which may be constructed from sheet metal and 30 standard wire with the aid of dies.

Fifth. To provide an accelerator accessory which may be readily assembled, and in which the parts are interchangeable with the corresponding elements of other similar accessories.

Sixth. To provide a foot accelerator for vehicles, which may be readily installed without damaging existing structure, and which may be conveniently operated without interfering with the normal operation of other 40 mechanism associated with the vehicle.

Seventh. To provide a combined hand and foot operable control device, wherein either hand or foot operation may be effected entirely independently of each other.

Eighth. To provide for convenient location of a foot accelerator attachment within a vehicle.

Ninth. To provide vehicle accelerating 50 mechanism various elements of which are

readily adjustable to produce most efficient operation.

Tenth. To provide various improvements in the details of construction, assemblage and operation of automobile accelerators, which 55 will improve the operation and reduce the cost of such appliances.

A clear conception of the construction, installation and operation of one embodiment of the present invention may be had by referring to the drawing accompanying and forming a part of this specification, in which like reference characters designate the same or similar parts in the various views.

Fig. 1 is a fragmentary side elevation of 65 a Ford type of motor having an improved accelerator applied thereto, the view being taken looking toward the carburetor side of the engine.

Fig. 2 is a fragmentary side elevation of a 70 Ford type of motor having the improved accelerator applied thereto, the view being taken looking toward the foot control lever side of the engine.

Fig. 3 is a fragmentary top view of a Ford 75 type of motor having the improved accelerator applied thereto.

Fig. 4 is an enlarged end elevation of the 80 improved accelerator supporting bracket and some of the associated elements.

The Ford type of engine to which the specific embodiment of the invention shown and described herein, is especially applicable as an accessory, comprises in general a plurality of vertical power cylinders 3 located in 85 advance of and below the driver's compartment of the car; a carburetor 2 disposed laterally adjacent to the rear cylinders 3; a fuel supply manifold 4 detachably associated with the carburetor 2 by means of bolts 11 and 90 providing a fuel feed connection between the carburetor 2 and the cylinders 3; and control levers 25 associated with the rear portion of the motor and extending upwardly into the driver's compartment of the vehicle through 95 slots in the foot boards 14. The vertical cylinders 3 are arranged in pairs separated by a space 26 which provides a transverse opening extending across the engine. The carburetor 2 is provided with a horizontally oscillatable 100

fuel control lever 5 which is movable in a counter-clockwise direction from the position shown in Fig. 3, to admit increased quantities of fuel and thus accelerate the speed of the engine. The various elements just described comprise standard equipment on any Ford type of automobile.

The improved accelerator mechanism forming the subject of the present invention, 10 comprises a horizontal cross rod movable and extending transversely across the engine through the space 26, and having one end detachably pivotally connected to the swinging end of the fuel control lever 5; a sheet 15 metal angle bracket 10 detachably but rigidly connected to the lower flange of the fuel supply manifold 4 by means of the clamping bolts 11; a helical tension spring 9 one end of which is attached to the movable transverse rod 7 and the opposite end of which is 20 detachably secured to the stationary bracket 10; a sheet metal lever or bell crank 6 vertically pivotally supported upon the bracket 10 by means of a pivot pin 19; a collapsible connector or chain 12 connecting the forwardly extending arm of the bell crank 6 with the transverse rod 7 at a point closely adjacent to the lever 5; and foot and hand manipulable rods 8, 20 associated with the bell crank 6 25 and with the transverse rod 7 respectively.

The transverse rod 7 is formed of standard wire having one end bent at ninety degrees to provide a pivotal connection with the lever 5 and having its opposite end threaded to receive an adjustable bifurcated nut 24. The sheet metal angle bracket 10 is formed as shown in detail in Figs. 3 and 4, with a lower recess 27 fitting over the manifold 4 and with notches 28 adapted to engage the bolts 11. 35 The bracket 10 may be applied and removed without entirely removing the bolts 11, by virtue of the downwardly open notches 28. The forward end of the bracket 10 is provided with an integral stop 13 extending upwardly beyond the horizontal plane of movement of the lever 6 and limiting the clockwise movement of the lever 6 as viewed in Fig. 3.

The foot operable rod 8 is likewise formed of standard wire and has its forward extremity bent downwardly and detachably pivotally connected to the swing end of the arm 18 of the bell crank 6. The rod 8 penetrates the foot boards 14 at the right of the foot control levers 25 as viewed from the driver's seat, and projects a short distance above the foot boards 14. The upper rear extremity of the rod 8 is rigidly secured to a foot button 15 which may be pressed from sheet metal and is preferably provided with a rubber contact pad. A guide plate 16 attached to the foot board 14, embraces the rod 8 and forms a guide therefor. A sheet metal foot rest 17 is secured to the foot boards 14 rearwardly of and below the button 15 as shown in Fig. 1,

and serves as a steadyng means for the operator's foot.

The hand operable rod 20 forms standard equipment of the car and extends parallel with the steering post, having a manipulating handle of well known construction at its upper end. The lever 21 is oscillatable by rotation of the rod 20 and has an opening in its swinging lower end which loosely embraces a pivot pin 23 formed integral with the slidble block 22. The slidble block 22 has a transverse through opening which slidably embraces the rod 7, the degree of sliding between the block 22 and the rod 7 being variable by adjustment of the nut 24 along the threaded end of the rod 7.

In order to apply the improved accelerator attachment to a Ford type of automobile, it is necessary only to remove the cross-connection between the levers 21, 5, which is furnished by the manufacturer; to release the clamping bolts 11 and apply the bracket 10; to attach the transverse rod 7 to the levers 21, 5; and to position the foot operable rod 8, plate 16 and foot rest 17 as shown. This application of the accelerator may be made by any novice within a few minutes.

During normal operation of the accelerator mechanism, the fuel control lever 5 may be either alternatively or simultaneously adjusted either by hand or foot or both at the will 95 of the operator. In order to effect hand operation, it is only necessary for the operator to rotate the rod 20 in a clockwise direction as viewed in Fig. 3, whereupon the lever 21 moves the block 22 to the left against the nut 24 and shifts the transverse rod 7 to the left. This motion of the rod 7 causes the fuel control lever to move in a counterclockwise direction, the spring 9 being simultaneously stretched and the chain 12 being flexed without in any manner disturbing the position of the lever 6 and of the rod 8. As the rod 20 is released, the spring 9 automatically becomes effective to urge the rod 7 and the lever 5 to the right until the fuel supply is entirely cut off.

In order to effect foot operation of the accelerator, it is only necessary for the operator to step upon the button 15 or otherwise push downwardly against the rod 8, whereupon the bell crank 6 swings in counter-clockwise direction about the pivot 19 as viewed in Fig. 3, and exerts a pull upon the chain 12 and rod 7. This pull causes expansion of the spring 9 and movement of the fuel control lever in a counter-clockwise direction, the rod 7 merely sliding within the block 22 without affecting the position of the lever 21 and of the rod 20. As the pressure upon the rod 8 is released, the spring 9 automatically urges the rod 7 and the lever 5 to the right thereby returning the bell crank to a position of engagement with the stop 13 of the bracket 10 and also returning

the rod 8 and button 15 to normal position. With the mechanism in normal position and the lever 5 in valve closed position, the chain 12 should be taut and the block 22 should be 5 in contact with the nut 24 in order to insure immediate operation of the fuel control valve by adjustment of either of the control rods 8, 20.

It will be obvious from the foregoing description, that the fuel supply lever 5 may be adjusted independently either by hand or foot, and that the adjustments may be made simultaneous if desired. The appliance is readily applicable as an accessory to any Ford 15 type automobile without damaging existing structure of the car and without interfering with the normal operation of other mechanism. With the aid of the present improvement, the foot accelerator may be conveniently located to the right of and adjacent to the foot control levers 25.

The bracket 10, lever 6, button 15 and plate 16 may all be constructed of relatively heavy sheet metal with the aid of dies, thereby reducing to a minimum the cost of construction and insuring interchangeability of these parts. The rods 7, 8 may be formed of standard relatively stiff wire properly bent to clear existing structure of Ford type of vehicles, and 30 the spring 9 and chain 12 are of relatively standard construction thus further minimizing the cost of manufacture. The various parts of the mechanism are preferably nickel plated thereby giving the structure a neat and attractive appearance. While the device is described herein as being specifically applicable to Ford type automobiles, it will be obvious that the novel principles are more generally applicable to other types of engines.

It should be understood that it is not desired to limit the invention to the exact details of construction and operation herein shown and described, for various modifications within the scope of the claims may occur to persons skilled in the art.

It is claimed and desired to secure by Letters Patent:—

1. In combination with an engine having 50 a plurality of cylinders and a fuel control located at one side thereof, a hand operable rod located at the opposite side of said cylinders, a transverse rod connected to said fuel control and crossing said engine between said 55 cylinders, a one-way lost motion connection between said rods, a foot operable rod located on the fuel control side of said cylinders, a bell crank lever having one arm connected to said foot operable rod, means for positively arresting and limiting the movement 60 of said lever in one direction, and a flexible direct connection between the other arm of said lever and said transverse rod.

2. In combination with an engine having 65 a plurality of cylinders and a fuel control

located at one side thereof, a hand operable rod located at the opposite side of said cylinders, a transverse rod crossing said engine and connected at one end to said fuel control, a one-way lost motion connection between 70 the opposite end of said rod and said hand operable rod, a foot operable rod located on the fuel control side of said cylinders, a bell crank lever having one arm connected to said foot operable rod, means cooperable directly 75 with said transverse rod for constantly urging said transverse rod and said lever in one direction, and means for positively arresting and limiting movement of said lever by said urging means. 80

3. In combination with an engine having a plurality of cylinders and a fuel control located adjacent thereto, a hand manipulable rod, a transverse rod associated with said fuel control, a lost motion connection between said rods, a foot manipulable rod, a bell crank lever pivotally connected to said foot manipulable rod, a direct chain connection between said lever and said transverse rod, and a spring cooperable directly with and constantly urging said transverse rod in one direction. 90

4. As an article of manufacture, an accelerator attachment comprising a transverse rod having a lost motion connection at 95 one end, a bracket, a spring directly connecting said rod and said bracket, a bell crank lever mounted on said bracket, a direct flexible connection between said lever and said rod, and a foot operable rod secured to said 100 lever.

5. As an article of manufacture, an accelerator attachment comprising a transverse rod, an element adjustable longitudinally of said rod, a member coactable with said element to move said rod, a bracket, a direct resilient connection between said rod and said bracket, a lever pivotally associated with said bracket, a direct flexible connection between 105 said lever and said rod, and a foot manipulable rod secured to said lever. 110

6. As an article of manufacture, an accelerator attachment comprising a transverse rod, a lost motion connector associated with said rod, a bracket, a spring directly connecting said rod and said bracket, a bell crank lever pivotally associated with said bracket, a stop for said lever formed integral with 115 said bracket, a connection between said lever and said rod, and a foot manipulable rod secured to said lever. 120

7. As an article of manufacture, an accelerator attachment comprising a transverse rod, an element adjustable longitudinally of said rod, a member coactable with said element to move said rod, a bracket, a spring directly connecting said rod and said bracket, a bell crank lever pivotally associated with said bracket, a stop for said lever formed integral with 125 said bracket, a connection between said lever and said rod, and a foot manipulable rod secured to said lever. 130

lever and said rod, and a foot manipulable rod secured to said lever.

8. As an article of manufacture, an accelerator attachment comprising a transverse rod, an element adjustable longitudinally of said rod, a member engageable with said element to move said rod, a sheet metal bracket, a spring directly connecting said

rod and said bracket, a sheet metal bell crank lever pivotally secured to said bracket, a chain connecting one arm of said lever with said rod, and a foot manipulable rod pivotally connected to the other arm of said lever.

In testimony whereof, the signature of the inventor is affixed hereto.

ROBERT M. HENDERSON.
